[57] CLAIM

The ornamental design for a vibrating game projector or similar article, as shown and described.

DESCRIPTION

FIG. 1 is a front elevational view of a vibrating game projector or similar article showing our new ornamental design;

FIG. 2 is a side elevational view thereof;

FIG. 3 is a rear elevational view thereof; and

FIG. 4 is a top plan view thereof.

The broken line showing of game pieces is for illustrative purposes only.

The bottom of the game or similar article is plain and unadorned.

FIG. 3

FIG. 1

FIG. 2

FIG. 4
